(No Model.)

H. MALLEBRE.

UPRIGHT PIANO ACTION FRAME.

No. 398,635.

Patented Feb. 26, 1889.

UNITED STATES PATENT OFFICE.

HENRY MALLEBRÉ, OF NEW YORK, N. Y.

UPRIGHT-PIANO ACTION-FRAME.

SPECIFICATION forming part of Letters Patent No. 398,635, dated February 26, 1889.

Application filed November 16, 1888. Serial No. 290,999. (No model.)

To all whom it may concern:

Be it known that I, HENRY MALLEBRÉ, of the city, county, and State of New York, have invented certain new and useful Improvements in Upright-Piano Action-Frames, of which the following is a specification.

This invention relates to certain improvements in action-frames for upright pianos, whereby the key-bottom is prevented from sagging, so that changes in the relative positions of the parts of the actions are avoided, a more effective operation of the actions obtained, and the regulating of the same facilitated; and the invention consists of an upright-piano action-frame in which the standards of the frame are suspended from projecting brackets at the upper part of the string-frame, said projections being provided with sockets or recesses into which corresponding noses at the upper ends of the standards are seated. The lower ends of the standards are connected by screw-bolts with the key-bottom, and attached to shoulders and threaded shanks of said bolts by screw-nuts, as will be fully described hereinafter, and finally be pointed out in the claims.

In the accompanying drawings, Figure 1 represents a side elevation, partly in section, of my improved action-frame for upright pianos, showing the connection of the frame with the string-frame and key-bottom; and Fig. 2 is a detail side view of one of the standards of the action-frame.

Similar letters of reference indicate corresponding parts.

Referring to the drawings, A are the standards of my improved upright-piano action-frame. Each standard A is hung by a tapering nose, a, to a projecting bracket, B, which is cast integral with the string-frame C of the upright piano, said bracket being provided with a tapering socket or recess, b, that corresponds to the shape of the nose a of the standard A. For the purpose of preventing the lifting out or detaching of the standard A from the projection B, the upper end of the same is provided with a set-screw, d, that bears on the beveled front edge of the bracket B, and retains thereby the standard firmly in position on the same, as shown in Fig. 1.

To the standards A of the action-frame are mounted, in the usual manner, the different rails required for supporting the actions, as

customary in piano-action frames. The lower end, e, of each standard A is bent in forward direction and connected with the upper end of a screw-bolt, D, which is screwed into the key bottom E. The lower end, e, of the standard A rests on a shoulder, e', at the upper end of the screw-bolt D, and is retained thereon by a screw-nut, D', which engages the threaded shank e² of the screw-bolt D. By the screw-bolt connection of the standards A with the key-bottom E the lowering or sagging of the same is prevented, so that the parts of the actions are retained in their proper relative positions. By the rigid connection of the string-frame and key-bottom by the intermediate standards of the action-frame the actions are prevented from getting out of order, and can be regulated easily and in less time, and operated with great precision. By the tight fastening of the standards by the screw-nuts on the threaded ends of the bolts the rigid position of the key-bottom, action-frame, and actions is obtained, and thereby the accurate and reliable working of the actions produced.

Having thus described my invention, I claim as new and desire to secure by Letters Patent—

1. In upright-piano action-frames, the combination of a string-frame having projecting brackets and recesses or sockets in said brackets, upright standards provided with beveled noses resting in said sockets, and screw-bolts connecting the lower ends of the standards with the key-bottom, substantially as set forth.

2. In upright-piano action-frames, the combination, with a string-frame having projecting brackets provided with recesses or sockets, upright standards for the actions, said standards having beveled noses at the upper ends resting in said sockets, set-screws passing through the upper ends of the standards and engaging the brackets, and screw-bolts connecting the lower ends of the standards with the key-bottom, said bolts having shoulders and threaded shanks for the fastening screw-nuts, substantially as set forth.

In testimony that I claim the foregoing as my invention I have signed my name in presence of two subscribing witnesses.

HENRY MALLEBRÉ.

Witnesses:

PAUL GOEPPEL,
CARL KARP.
